UNITED STATES PATENT OFFICE.

BENJAMIN J. HOOVER, OF MERIDIAN, MISSISSIPPI.

SAFETY APPLIANCE.

1,369,893.

Specification of Letters Patent. Patented Mar. 1, 1921.

Application filed September 28, 1920. Serial No. 413,268.

To all whom it may concern:

- Be it known that I, BENJAMIN J. HOOVER, a citizen of the United States, residing at Meridian, in the county of Lauderdale and State of Mississippi, have invented certain new and useful Improvements in Safety Appliances, of which the following is a specification, reference being had therein to the accompanying drawing.
- 10 The present invention relates to safety appliances for railroad cars which are equipped with air brakes, and the invention has for its primary object the provision of a novel and improved device for automatically applying the brakes when a truck with which the device is used, becomes derailed or should the brake beams drop, whereby to stop the train immediately, and avoid a wreck or other damage.
- 15 A further object of the invention is the provision of a novel valve to be used in the train pipe for "bleeding" or exhausting the air therefrom in an emergency, such as the derailing of the truck or falling of one or both brake beams, and such valve being of novel and improved construction to render it particularly advantageous and efficient for the intended purpose.
- 20 Another object is the provision of novel means carried by a truck for operating the valve in the event that the truck is derailed or one or both of the brake beams dropped, the valve having means coöperating therewith to open the valve in such an emergency.
- 25
- 30
- 35
- 40
- 45

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a bottom perspective view of the truck of a railroad car showing the present appliance installed.

Fig. 2 is an enlarged side elevation of the appliance, portions being shown in section.

Fig. 3 is an enlarged cross section of the valve taken on the line 3—3 of Fig. 2.

Fig. 4 is a longitudinal section of the valve taken on the line 4—4 of Fig. 3.

55 In carrying out the invention, there is interposed between two sections of the train

pipe 7 adjacent to the truck, a safety valve comprising the casing 8 having its opposite ends secured to the adjacent ends of the pipe sections, as seen in Fig. 4, and said 60 casing has an outlet port 9 extending laterally between the ends thereof, and preferably located at the top of the casing, as shown. A gasket 10 of rubber or other suitable material is fitted within the port 9, and 65 the casing has an annular groove 11 and flange 12 surrounding the port, engaged by the annular groove 13 and flange 14, respectively, of the gasket 10, as seen in Fig. 4. A valve member or cap 15 is carried by 70 an arm 16, which arm has one end pivoted, as at 17, between lugs or ears 18, extending from the casing 8 at one end, whereby said valve member can swing to and from the gasket and port 9. The member or cap 15 75 is preferably recessed, as at 19, to fit over the protruding portion of the gasket, and forms a tight closure.

A latch is provided for holding the valve member 15 closed, and for releasing it in an 80 emergency, to let the air escape from the train pipe 7 and thus apply the brakes automatically in the well known manner. That end portion of the casing 8 opposite to the end to which the arm 16 is pivoted, is 85 turned down, as at 20, and the latch comprises a ring or collar 21, rotatable on the portion 20, and provided with a hook or angular lug 22 to engage over a lug 23 projecting from the free end of the arm 16, 90 which arm extends longitudinally of the casing, across the port 9. The lug 23 is rounded at that side engaged by the hook 22, whereby to press the valve member 15 95 tightly against the gasket, and thus prevent leakage of air.

The ring 21 has arms 24 and 25 extending radially therefrom substantially at right angles with one another, and the arm 24 is tubular, having a bore 26 for holding a 100 detent, which, as shown, comprises a ball 27 within the inner end of said bore to engage within a recess or notch 29 in the portion 20 of the valve casing, when the hook 22 is engaged with the lug 23, thereby preventing 105 accidental rotation of the ring 21. A coiled expansion spring 28 is disposed within the bore 26, and bears at its inner end against the ball 27 to snap same into the notch 29, yet to permit said ball to be forced outwardly into the bore 26 when the ring 21 is 110 forcibly turned. The arms 24 and 25 can

also be used as handles for turning the latch to engage the valve arm 16.

An angular rod 30 co-operates with the arms 24 and 25, to constitute a loop, as seen in Fig. 3, and one terminal 31 of the rod 30 is bent at an angle and is screw threaded into the outer end portion of the arm 24, to retain the spring 28 in place, said spring being confined between said terminal 31 and ball or detent 27. A lock nut 32 is preferably threaded on a terminal 31 to bear against the arm 24, and the other terminal of the rod 30 is sprung into a notch 33 in the end of the arm 25, thereby preventing 15 accidental rotation of the terminal 31 in the arm 24, and also engaging the rod 30 and arm 25 with one another.

A valve-operating lever or member 34 is carried by the truck, and comprises a bar 20 bent to provide parallel lever portions 35 and 36, and a yoke 37 connecting the arms of said portions at one side of their fulcrums, and the opposite arm of the portion 35 has an upwardly offset terminal 38 projecting through the loop of the valve latch composed of the arms 24 and 25 and rod 30, as seen in Fig. 3. The portions 35 and 36 are located longitudinally below the sand plank 42, of the truck, and are fulcrumed 25 or pivoted between their ends as at 39, within the lower bifurcated heads 40 of bolts or stems 41 which extend upwardly and through the plank 42, and said bolts or stems are secured in place by means of nuts 43 thereon. The lever or member 34 can thus rock or swing about a transverse horizontal axis below the sand plank or board 42 of the truck, whereby the terminal 38 will move vertically to be brought into contact with the arm 25 above or the lower horizontal portion of the rod 30 underneath. A bow spring 44 is engaged intermediate its 40 ends to one of the bolts or stems 41 and its terminals bear downwardly on the portion 35 of the lever, whereby to maintain the lever or member 34 in normal position, and permitting the lever to yield and swing in either direction. The arms of the portions 35 and 36 extend under the brake beams 45, 45 whereby should either beam drop accidentally, as sometimes happens, the beam in falling on one arm of the lever 34, would swing said lever, and thereby either raise or lower the terminal 38, so as to strike the arm 25 or rod 30, and thereby turn the ring to remove the hook 22 therefrom from the lug 23. This would release the valve member 15, so that the air pressure would swing said valve member open and permit the air to 60 escape, thereby applying the brakes, and avoiding a wreck or damage due to the dropping of the brake beam. The train would therefore be stopped and the defect can be remedied, before proceeding, and when the valve is again closed and latched,

the lever 34 will assume its normal position due to the influence of the spring 44.

Should the truck become derailed, due to the spreading of the rails, broken rails, broken arch bars, or the like, the skewing 70 of the truck would move the lever 34 with it, thereby swinging the terminal 38 sidewise, and either striking the arm 24 or the opposite vertical portion of the rod 30, which would turn the ring 31 and release the valve 75 member 15, so that the air would escape from the pipe 7 and thus apply the brakes. The present appliance therefore provides for safety, in that the train pipe is opened to the atmosphere and the brakes applied 80 should one of the brake beams drop, or should the truck become derailed for any reason whatever.

Having thus described the invention, what is claimed as new is:— 85

1. The combination with a railroad car truck, of a lever fulcrumed thereto, and extending under a brake beam of the truck, and a train pipe valve arranged to be operated by said lever when swung by the dropping of said brake beam thereon or by the skewing of the truck.

2. The combination with a railroad car truck, of a lever fulcrumed to the truck and extending longitudinally under the brake 95 beams to be swung by the dropping of either beam, and a train pipe valve arranged to be operated by the swinging movement of said lever or by the skewing of the truck.

3. The combination with a railroad car 100 truck, of a lever comprising parallel lever portions, a yoke connecting said portions and a terminal extending from one of said portions, means fulcruming said portions between their ends to the truck with said 105 portions extending under the brake beams, and a train pipe valve arranged to be operated by said terminal when the lever is swung by the dropping of a brake beam thereon, or when the truck is skewed. 110

4. The combination with a railroad car truck, of a lever fulcrumed to the truck and extending under a brake beam, a train pipe valve having a loop operable for opening the valve, said lever having a terminal 115 extending into said loop, and spring means for maintaining said lever yieldingly in normal position with said terminal within said loop, said valve being operated by the movement of said loop by said terminal due to 120 the swinging of the lever or the skewing of the truck.

5. The combination with a railroad car truck, of a lever fulcrumed between its 125 ends to the truck and extending longitudinally under the brake beams, a bow spring having its terminals bearing on the arms of the lever to yieldingly maintain the lever in normal position, and a train pipe valve having a loop mounted for turning move- 130

ment to open the valve, said lever having a terminal projecting within said loop for turning the loop by the swinging movement of the lever or the skewing of the truck.

5 6. A safety appliance comprising a valve casing for a train pipe and having an outlet port, a valve member to close said port, means for holding the valve member in closed position and to release said valve member, and single means carried by a car truck and controlling said first named means and operable to release the valve member either by the dropping of the brake beams or the skewing of the truck.

10 7. A safety appliance comprising a valve casing having an outlet port, a valve member for closing said port, a ring mounted for turning movement on the casing and having means for holding said valve member in closed position in one position of the ring, a loop carried by said ring, and means to be carried by a car truck to be swung by the dropping of a brake beam or the skewing of the truck and having a portion 15 projecting within said loop for movement therein in various directions and to contact with the loop for turning said ring to release said valve member.

20 8. A safety appliance comprising a valve casing having an outlet port, a valve member for closing said port, a ring mounted for turning movement on the casing and having means for holding said valve member in closed position in one position of said ring, 25 said ring having a pair of arms extending

therefrom at an angle with one another, and an angular rod having one terminal screw-threaded into one arm and its other terminal engaged with the other arm, to constitute a loop with said arms, and means 40 to be carried by a car truck and having a portion to extend within said loop for movement therein to contact with and swing said loop so as to turn said ring to release the valve member. 45

9. A safety appliance comprising a valve casing having an outlet port, a valve member to close said port, a ring mounted for turning movement on the casing and having a portion for holding said valve member in closed position in one position of said ring, said ring having arms extending therefrom at an angle with one another, one of said arms being tubular, a ball in said tubular arm, the casing having a notch for the engagement of said ball, an angular rod having one terminal screw threaded into the tubular arm, an expansion spring confined within said tubular arm between said terminal of the rod and ball, the other arm having 50 a notch in which the other terminal of said rod is sprung, and means to be carried by a car truck having a portion to project between said rod and arms, to contact therewith and turn said ring for releasing the 55 valve member. 60

In testimony whereof I hereunto affix my signature.

BENJAMIN J. HOOVER.
